UNITED STATES PATENT OFFICE.

FELICE FRANCIS MALONEY, OF SUDBURY, CANADA.

DESIGN FOR A COMB, PAPER-CUTTER, NAIL-CLEANER, AND WATCHCASE-OPENER.

SPECIFICATION forming part of Design No. 32,774, dated June 5, 1900.

Application filed March 15, 1900. Serial No. 8,848. Term of patent 7 years.

To all whom it may concern:

Be it known that I, FELICE FRANCIS MALONEY, a subject of the Queen of Great Britain, residing at Sudbury, in the Province of Ontario, Dominion of Canada, have invented and produced a new and original Design for a Comb, Paper-Cutter, Nail-Cleaner, and Watchcase-Opener, of which the following is a specification.

10 This invention relates to a new and original design for a comb, paper-cutter, nail-cleaner, and watchcase-opener; and it has for its object to provide a design of this character that shall be both useful and ornamental.

15 The leading feature of the design resides in a flat-sided body of an approximate cigar shape and having within the plane thereof a comb member extending longitudinally of the body and whose teeth are grouped at one side 20 thereof, with their outer edges forming a portion of one of the convexed edges of the same.

The minor features of the design are the body having the convexed edge opposite the comb member beveled at both sides and being tapered at one end into a beveled point and provided at its opposite end with a straight beveled edge.

In the drawings, Figure 1 is a plan view of a comb, paper-cutter, nail-cleaner, and watchcase-opener embodying the herein-described design. Fig. 2 is a transverse sectional view

thereof. Fig. 3 is a cross-sectional view of the article.

Referring particularly to the drawings, the numeral 1 designates a flat-sided body of an approximate cigar shape or having a lanceolate form, said body being tapered at one end into a beveled nail-cleaning point 2 and provided at its opposite end with a straight beveled watchcase-opening edge 3. The said body is further provided within the plane thereof with a comb member 4, extending longitudinally of the body nearly the entire length thereof and whose teeth are grouped at one side of the body, with their outer edges forming a portion of one of the convexed edges thereof. The convexed paper-cutting edge of the cigar-shaped body opposite the comb-teeth is beveled at both sides, as indicated at 5, thereby completing the design.

What is claimed is—

The design for a comb, paper-cutter, nail-cleaner, and watchcase-opener herein shown and described.

In testimony that I claim the foregoing as my own I have hereto affixed my signature in the presence of two witnesses.

FELICE FRANCIS MALONEY.
